UNITED STATES PATENT OFFICE

HOWARD M. BARBER, OF PAWCATUCK, CONNECTICUT, ASSIGNOR TO C. B. COTTRELL & SONS COMPANY, OF WESTERLY, RHODE ISLAND, A CORPORATION OF DELAWARE

MULTICOLOR ROTARY PRINTING PRESS

Application filed February 7, 1930. Serial No. 426,577.

My present invention is directed especially to a rotary web printing press which is designed for so called bag printing, whereby the printed web which may be paper or any thin or loosely woven material, such as burlap, will have the successive printing thereon in one or more colors placed at different distances apart, according to the length of the sheets which are to be cut from the web.

10 My invention comprises one or more impression cylinders of a predetermined diameter and one or more plate cylinders of a predetermined diameter, the impression cylinder or cylinders being of the same diameter as the plate cylinder or cylinders or a multiple thereof.

My invention further comprises means whereby the sizes of either the plate or impression cylinders, or both, may be readily 20 and easily changed without rebuilding the press, by the employment of cylinder shell members of varying diameters removably secured to the cylinder shaft members.

A practical embodiment of my invention 25 is shown in connection with a three color rotary web printing press such as that shown, described and claimed in my copending application, Serial No. 318,506, filed November 10th, 1928.

30 Fig. 1 represents a detail side elevation illustrating coating plate and impression cylinders of the same diameter.

Fig. 2 represents a similar view illustrating the impression cylinders as twice the diameter of the plate cylinders.

35 Fig. 3 represents a detail side view of one of the cylinders (in the present instance a plate cylinder) on an enlarged scale, a portion of the longitudinally divided cylinder shell member being broken away to more clearly illustrate the parts inside the same.

Fig. 4 represents an end view of the cylinder.

40 Fig. 5 represents a longitudinal central section taken in the plane of the line V—V of Fig. 4, looking in the direction of the arrows.

Fig. 6 represents a longitudinal section 45 taken in the planes of the lines VI—VI of

Fig. 4, looking in the direction of the arrows.

The main frame of the printing press is denoted by 1. The three plate cylinders illustrated are shown as comprising shaft members 2, 3 and 4 to which in Fig. 1 shell members 5, 6 and 7 respectively of one diameter are removably secured and to which in Fig. 2 shell members 8, 9 and 10 respectively of another diameter are removably secured. 55

The two impression cylinders illustrated are denoted as comprising shaft members 11 and 12 to which shell members 13 and 14 of a predetermined diameter are removably secured. These impression cylinder shaft members 11 and 12 are shown as mounted in horizontally adjustable bearings 15 and 16. The shell members for the plate and impression cylinders are shown as longitudinally divided for facilitating the changing of the 70 shell members of one diameter to shell members of another diameter.

The impression cylinders are shown of the same diameter as the plate cylinders in Fig. 1 and are shown as twice the diameter of the 75 plate cylinders in Fig. 2 but it is to be understood that these are only two examples of the relative sizes of the plate and impression cylinders as the impression cylinders may not only be the same diameter as the 80 plate cylinders but also any multiple thereof.

In Fig. 1 the upper plate cylinder gear 17 is shown as being driven from the upper impression cylinder gear 18 and the lower plate cylinder gears 19 and 20 as being driven 85 from the lower impression cylinder gear 21. In Fig. 2 the upper plate cylinder gear 22 is shown as being driven from the upper impression cylinder gear 17 and the lower plate cylinder gears 23, 24 as being driven from 90 the lower impression cylinder gear 21.

The upper and lower impression cylinder gears 17 and 21 are connected for synchronous action through the registering gear 25, the shaft 26 of which is adjustable horizontally along slots 27 in brackets 28, carried by the main frame 1. 95

As the means shown herein for securing the shell members to their shaft members is the same for both the plate and impression cylinders.

ders, I will describe specifically only one of said means, viz., the means for securing the plate cylinder shell member 5 to its shaft member 2. The shaft member 2 is provided with a sleeve 29 keyed thereto, which sleeve has a flange 30 projecting laterally therefrom. This flange has radial slots 31 at intervals around the same. Between the walls of each slot a swinging clamp bolt 32 is pivot-
 10 ed at 33, the inner end of which bolt may be provided with a stop 34 arranged to be brought into engagement with the sleeve 29, to limit the releasing movement of the bolt. A curved shoe 35 is loosely mounted on the
 15 bolt between the nuts 36 and an expansion spring 37.

The longitudinally divided shell member 5 is provided at each end with a flange 38 concentric with the longitudinal axis of the
 20 shaft member 2, the inner wall of which flange fits the peripheral face of the sleeve flange 30. This shell member flange 38 has radial slots 39 forming extensions of the
 25 radial slots 31 in the sleeve flange for receiving the clamp bolt 32 when it is swung into its locking position with the shoe 35 in engagement with the outer wall of the said flange 38. The tightening of the clamp bolt nuts 36 will serve to lock the divided shell
 30 member to the shaft member.

To properly position the sections of the divided shell member on the shaft member I provide the shaft member sleeve with radial dowels 40, arranged to enter holes 41 in the
 35 shell member flange 38.

While I have shown four shell clamping and four shell positioning devices for each cylinder, it is obvious that the number may be varied to suit different requirements.

40 It will be understood that the divided shell member flange 38 is located the same distance from the axis of the shaft member on all of the shell members of different diameters so that they may be readily interchanged to
 45 form cylinders of various diameters.

The impression cylinder 13 is shown as moved into position to coact with its plate cylinder 5 or 8 by the following means:

40 A hand wheel 42 has its cross shaft 43 provided with a bevel gear connection 44, 45 at each side of the machine frame with a screw shaft 46 engaging the bearing 15 which is slidable along a guideway 47. A set screw
 45 is arranged in position to engage the bearing 15 and lock it in its adjusted position.

The impression cylinder 14 is shown as moved into position for simultaneous coaction with either the two plate cylinders 6, 7 or
 60 9, 10, by the following means:

A handle 49 has its cross shaft 50 provided with a bevel gear connection 51, 52 at each side of the main frame with a screw shaft 53 which engages the bearing 16, slidable along
 65 the guideway 54. A set screw 55 is arranged

in position to engage the bearing 16 and lock it in its adjusted position.

A change gear drive is provided for the impression and plate cylinders, which change gear drive is shown as including a change gear of the same diameter as the selected plate cylinders. The rocking support for the change gear is denoted by 56 and it carries a stud shaft 57. This stud shaft serves in Fig. 1 as a mounting for the change gear 58 and in Fig. 2 as a mounting for the change gear 59. The means which I have shown for rocking the supports 56 to bring the selected change gear into driving connection with its impression cylinder gear 21 is shown as a hand wheel 60, the cross shaft 61 of which has a bevel gear connection 62, 63 with a worm shaft 64, the worm 65 meshing with a gear segment 66 carried by the rocking support 56.

70 The drive for either the change gear 58 or the change gear 59 is shown as a gear 67 on the shaft 68 which meshes with a gear 69 on the shaft 70. A gear 71 on this shaft 70 meshes with a gear 72 on the stud shaft 57.

75 The rocking support 56 may be locked in its adjusted position by means of a bolt 73 projecting through an elongated slot 74; a locking nut 75 being provided for said bolt.

80 The web 76 is shown as passing around suitable rollers 77, 78, 79, to and around the impression cylinder 13. From thence the web is shown as passing around the roller 80 to and around the impression cylinder 14. From thence the web is shown as passing around 100 the rollers 81 and 82 to the delivery point.

85 The above described means for adjusting the impression cylinders along horizontal planes to bring them into coaction with their plate cylinders forms part of the subject matter of my copending application Serial No. 318,506, hereinbefore referred to. Also, the change gear device for driving the printing mechanism forms part of the subject matter of the said copending application.

90 From the above description it will be seen that the sizes of the plate cylinders or the impression cylinders, or both, may be readily changed so long as the impression cylinders are of the same diameter as the plate cylinders or a multiple thereof.

95 It is evident that various changes may be resorted to in the construction, form and arrangement of the several parts without departing from the spirit and scope of my invention, and hence I do not intend to limit myself to the particular embodiment herein shown and described, but

100 What I claim is:—

1. In a multicolor rotary printing press, 125 plate and impression cylinders, the impression cylinders being the same diameter as the plate cylinders or a multiple thereof, each impression cylinder comprising a shaft member, a longitudinally divided shell member 130

of a predetermined diameter, said shell member being provided with concentric flanges at its ends having holes therein, dowels carried by the shaft member adapted to enter said holes to position the shell member on the shaft member, and clamping bolts hinged to the shaft member and provided with shoes adapted to be engaged with said flanges for securing the shell member to the shaft member.

2. In a multicolor rotary printing press, plate and impression cylinders, the impression cylinders being the same diameter as the plate cylinders or a multiple thereof, each plate cylinder comprising a shaft member, a longitudinally divided shell member of a predetermined diameter, said shell member being provided with concentric flanges at its ends having holes therein, dowels carried by the shaft member adapted to enter said holes to position the shell member on the shaft member, and clamping bolts hinged to the shaft member and provided with shoes adapted to be engaged with said flanges for securing the shell member to the shaft member.

3. In a multicolor rotary printing press, plate and impression cylinders, the impression cylinders being the same diameter as the plate cylinders or a multiple thereof, each plate and impression cylinder comprising a shaft member, a longitudinally divided shell member of a predetermined diameter, said shell member being provided with concentric flanges at its ends having holes therein, dowels carried by the shaft member adapted to enter said holes to position the shell member on the shaft member, and clamping bolts hinged to the shaft member and provided with shoes adapted to be engaged with said flanges for securing the shell member to the shaft member.

In testimony, that I claim the foregoing as my invention, I have signed my name this fifth day of February, 1930.

HOWARD M. BARBER.
